CIRCULARLY POLARIZED
OMNI-DIRECTIONAL ANTENNACROSS-REFERENCE TO RELATED
APPLICATIONS

This application is a continuation in part and claims priority under 35 U.S.C. § 119(e) to U.S. patent application Ser. No. 15/793,941, filed Oct. 25, 2017, entitled "Circularly Polarized Omni-Directional Antenna", the contents of which are hereby incorporated by reference.

BACKGROUND

Antennas are electrical devices which convert electric power into radio waves, and vice versa. They are usually used with a radio transmitter or radio receiver. In transmission, a radio transmitter supplies an electric current to the antenna's terminals, and the antenna radiates the energy from the current as electromagnetic waves (radio waves). In reception, an antenna intercepts some of the power of an electromagnetic wave in order to produce an electric current at its terminals, and is applied to a receiver to be amplified.

Typically an antenna consists of an arrangement of metallic conductors (elements), electrically connected (often through a transmission line) to the receiver or transmitter. Antennas may also include additional elements or surfaces with no electrical connection to the transmitter or receiver, such as parasitic elements, parabolic reflectors or horns, which serve to direct the radio waves into a beam or other desired radiation pattern.

Antennas can be designed to transmit and receive radio waves in all horizontal directions equally (omnidirectional antennas), or preferentially in a particular direction (directional or high gain antennas). An omnidirectional antenna is a class of antenna which radiates radio wave power uniformly in all directions in one plane, with the radiated power decreasing with elevation angle above or below the plane, dropping to zero on the antenna's axis. Omnidirectional antennas oriented vertically are widely used for nondirectional antennas on the surface of the Earth because they radiate equally in all horizontal directions, while the power radiated drops off with elevation angle so little radio energy is aimed into the sky or down toward the earth and wasted. Omnidirectional antennas are widely used for radio broadcasting antennas, and in mobile devices that use radio such as cell phones, FM radios, walkie-talkies, wireless computer networks, cordless phones, GPS as well as for base stations that communicate with mobile radios, such as police and taxi dispatchers and aircraft communications.

SUMMARY OF THE INVENTION

The following presents a simplified summary of the disclosure in order to provide a basic understanding of certain embodiments of this disclosure. This summary is not an extensive overview of the disclosure, and it does not identify key and critical elements of the present disclosure or delineate the scope of the present disclosure. Its sole purpose is to present some concepts disclosed herein in a simplified form as a prelude to the more detailed description that is presented later.

Provided are examples of circularly polarized omni-directional antennas and methods of fabricating such antennas. In one aspect, which may include at least a portion of the subject matter of any of the preceding and/or following examples and aspects, an antenna comprises a cylindrical

2

non-conductive cover comprising a base and a cap. The base and cap create a cavity for the antenna which separates the electrically connected portion of the antenna from the parasitically driven portion of the antenna.

5 The antenna further comprises a cable extending through an opening in the base such that a first end of the cable is located within the cavity and a second end of the cable is located external to the cover. The cable may be aligned with a center axis of the cover or may extend through the side of the cylinder portion. In some embodiments, the cable is a coaxial cable. The second end of the cable may include a coaxial radio frequency (RF) connector.

The antenna further comprises a plurality of electrically conducting elements spaced equidistantly about a circumference around the center axis of the cover. The plurality of conducting elements are curved about the circumference around the center axis of the cover. The plurality of conducting elements is located along the cylindrical portion of the antenna cover. Each conducting element of the plurality of conducting elements may be configured to include an angle of tilt between 16 degrees and 68 degrees from horizontal for single curve variants and between 16 and 90 degrees for multiple or compound curve elements. In particular embodiments, each conductive element of the plurality of conductive elements are configured to include an angle of tilt of 25 degrees from horizontal. The plurality of conducting elements may include four, five or six conductors. Each conducting element of the plurality of conducting elements may be a conductive trace within a printed circuit board (PCB) or may be copper wire.

In particular embodiments, the radius (r_i), in inches, from the center axis to the exterior surface of the inner cylinder portion is equal to approximately

$$\frac{2.055}{f};$$

40 wherein f is a desired operation frequency in gigahertz (GHz). In various embodiments the radius (r_i), in inches, from the center axis to the exterior surface of the inner cylinder portion is equal to approximately

$$\frac{1.14}{f}.$$

50 The radius may range from a value as low as

$$\frac{0.88}{f}$$

up to

$$\frac{4.24}{f}.$$

Other variations of this antenna may exist without a cylindrical cover. For example, the antenna may comprise a non-conductive cover with 4 flat sides in which each element within the plurality of conducting elements is bent or curved around the corners of the non-conductive cover.

Another variation of the antenna may include a number of conducting elements as few as 2 or as many as 16 elements.

Other implementations of this disclosure include corresponding devices, systems, and computer programs, configured to perform the actions of the described method. For instance, a system is provided comprising a receiver and an antenna as previously described. In some embodiments, the antenna is coupled to the receiver via a coaxial radio frequency (RF) connector that is coupled to the second end of the cable. In some embodiments, the antenna is directly coupled to a circuit board of a receiver. These other implementations may each optionally include one or more of the following features.

In another aspect, which may include at least a portion of the subject matter of any of the preceding and/or following examples and aspects, a method for constructing an antenna is provided. A cable is inserted through a first support collar such that an annular cavity is formed within the first support collar around the cable. The first support is bonded to a first end of the cable. A second end of the cable is then extended through an opening in a cover base that includes an inner cylinder portion having an interior surface and an exterior surface. The second end of the cable is located within a cavity defined by the interior surface of the inner cylinder portion and the first end of the cable is located external to the inner cylinder portion.

The cable is aligned with a center axis of the cover base. The second end of the cable is inserted through a second support collar such that the second support collar surrounds a portion of the cable within the cavity. The second collar is bonded to the cable. A plurality of conducting elements is positioned about the inner cylinder portion such that the conducting elements are spaced equidistantly around a circumference around the center axis. The cavity is sealed by covering the cover base with a cover cap such that an outer cylinder portion of the cover top surrounds the exterior surface of the inner cylinder portion.

These and other embodiments are described further below with reference to the figures.

BRIEF DESCRIPTION OF THE DRAWINGS

FIGS. 1A and 1B are perspective views of an example omni-directional antenna, in accordance with one or more embodiments.

FIG. 2A is a perspective cross-sectional view of an example cover for an omni-directional antenna, in accordance with one or more embodiments.

FIG. 2B is a cross-sectional view of an example omni-directional antenna, in accordance with one or more embodiments.

FIGS. 3A and 3B are perspective views of a base of an example cover for an omni-directional antenna, in accordance with one or more embodiments.

FIG. 4 is an example radiation pattern graph of an omni-directional antenna, in accordance with one or more embodiments.

FIG. 5 is an example method of constructing an omni-directional antenna, in accordance with one or more embodiments.

FIG. 6 is a perspective view of the plurality of conductive elements embedded in a printed circuit board (PCB), in accordance with one or more embodiments.

FIGS. 7A and 7B are perspective views of an example cylindrical cover within which the plurality of conductive elements are installed in accordance with one or more embodiments.

FIGS. 8A, 8B, and 8C show examples of an assembly of a non-cylindrical variation of the antenna comprising 4 flat sides in accordance with one or more embodiments.

FIGS. 9A and 9B are examples of antennas without the cover portion or cables in accordance with one or more embodiments.

DETAILED DESCRIPTION OF EXAMPLE EMBODIMENTS

Reference will now be made in detail to some specific examples of the invention including the best modes contemplated by the inventors for carrying out the invention. Examples of these specific embodiments are illustrated in the accompanying drawings. While the invention is described in conjunction with these specific embodiments, it will be understood that it is not intended to limit the invention to the described embodiments. On the contrary, it is intended to cover alternatives, modifications, and equivalents as may be included within the spirit and scope of the invention as defined by the appended claims.

For example, the techniques of the present invention will be described in the context of particular machines, such as drones. However, it should be noted that the techniques of the present invention apply to a wide variety of different machines that may require remote wireless control. As another example, the techniques of the present invention will be described in the context of particular wireless signals, such as Wi-Fi. However, it should be noted that the techniques of the present invention apply to a wide variety of different wireless signals, including Bluetooth, infrared, line of sight transmission mechanisms, as well as various other networking protocols.

In the following description, numerous specific details are set forth in order to provide a thorough understanding of the present invention. Particular example embodiments of the present invention may be implemented without some or all of these specific details. In other instances, well known process operations have not been described in detail in order not to unnecessarily obscure the present invention.

Various techniques and mechanisms of the present invention will sometimes be described in singular form for clarity. However, it should be noted that some embodiments include multiple iterations of a technique or multiple instantiations of a mechanism unless noted otherwise. For example, a system uses a processor in a variety of contexts. However, it will be appreciated that a system can use multiple processors while remaining within the scope of the present invention unless otherwise noted. Furthermore, the techniques and mechanisms of the present invention will sometimes describe a connection between two entities. It should be noted that a connection between two entities does not necessarily mean a direct, unimpeded connection, as a variety of other entities may reside between the two entities. For example, a processor may be connected to memory, but it will be appreciated that a variety of bridges and controllers may reside between the processor and memory. Consequently, a connection does not necessarily mean a direct, unimpeded connection unless otherwise noted.

Various embodiments are provided which describe a circularly polarized omni-directional antenna. Antennas as described herein may be referred to herein as an Ion antenna. Such antennas may have implementations in a variety of fields, including, but not limited to video piloting, drone vehicles (aircraft and ground, mesh networking, and Wi-Fi applications. In various embodiments, the antenna uses a central radiating element surrounded by curved parasitic

radiating elements. Such parasitic radiating elements may be wire type or printed on a printed circuit board (PCB). The antenna's central radiating element may be a center-fed sleeved dipole type which may be balanced by a separate sleeve choke dipole type with incorporated balun. The parasitic radiating elements may be curved about the central radiating element. The radiating elements may be fully encapsulated within a cover. Accordingly, various embodiments described in the present disclosure provide a lightweight omni-directional antenna that includes reduced sizing with greater durability and that may be implemented in a variety of systems.

With reference to FIGS. 1A and 1B, shown are perspective views of an example omni-directional antenna 100, in accordance with one or more embodiments. In various embodiments, antenna 100 includes cover 150 comprising a cap 152 and a base 154. Cap 152 and base 154 are depicted in FIGS. 1A and 1B with different shading to delineate each portion more clearly. In some embodiments, cable 102 extends into cover 150 through a cable opening 214 (further described below) in base 154. Thus a first end 102-A of the cable 102 is within the cover 150 and a second end 102-B of the cable 102 is external to the cover.

In various embodiments, cable 102 comprises a coaxial cable, such as an RG405 coaxial cable, for example. In other embodiments, cable 102 may comprise any other type of cable with the appropriate electromagnetic characteristics. In some embodiments, the cable may include a characteristic impedance between 25 and 100 Ohms. Such other cables may include an RG316 coaxial cable. In various embodiments, cable 102 may include several layers. The outermost layer may be a jacket, such as a 2.5 mm fluoropolymer jacket. The next layer may be an outer conductor or shield, such as a 2.20 mm layer of tin-soaked tin plated copper layer. The next layer may be an insulation layer, such as a 1.70 mm layer of solid extruded PTFE. The innermost layer may be an inner conductor, such as a 0.56 mm silver plated copper wire. In various embodiments, cable 102 may comprise a combination of one or more of the aforementioned layers.

The second end 102-B of cable 102 may be coupled to a coaxial radiofrequency (RF) connector 104. For example, coaxial RF connector 104 may be a SubMiniature version A (SMA) connector. As another example, coaxial RF connector 104 may be a U.FL connector, or any other suitable miniature RF connector for high-frequency signals. In some embodiments, coaxial RF connector 104 may be an integral part of cable 102. In various embodiments, various types of connectors 104 may be implemented to electrically connect antenna 100 with a circuit board of a transceiver or other device. In some embodiments, cable 102 may be directly coupled to a circuit board without using a connector 104. For example, second end 102-B may be directly soldered to the circuit board.

In some embodiments a support collar 106 may be symmetrically positioned around a portion of cable 102 adjacent to the coaxial RF connector 104. In some embodiments, the support collar 106 may comprise a metallic material. For example, support collar 106 may be a brass collar, such as a $\frac{3}{32}$ " by 0.31" brass collar, for example. The support collar 106, along with cable 102, forms the sleeve choke dipole type with incorporated balun. Support collar 106 may serve as a balun which may function to convert between a balanced signal (two signals working against each other where ground is irrelevant) and an unbalanced signal

(a single signal working against ground or pseudo-ground), and affecting the tuning of the antenna to a specific desired frequency.

The annular space between the interior surface of support collar 106 and the cable 102 may be filled with material 108. Such material 108 may be used to further secure support collar 106 to cable 102 and/or coaxial RF connector 104. For example, material 108 may include a combination of one or more of a solder and a glue, such as polyamide glue. In some 10 embodiments, material 108 comprising polyamide glue may comprise a dielectric material which may affect the effective balancing effect. As such, the amount of material 108 used within support collar 106 may affect the overall length and/or width of support collar 106. In some embodiments, material 108 may function as electrical and/or thermal insulation. Support collar 106 may additionally function to support a portion of cable 102 from directional forces to prevent bending of cable 102. In some embodiments a segment 103 of the cable 102 may exist unsupported or 15 uncovered between base 154 and support collar 106 which may allow antenna 100 to bend or flex about segment 103. The structure of antenna 100 is symmetrical about a longitudinal center axis 11.

With reference to FIGS. 2A and 2B, shown are perspective cross-sectional views of antenna 100 and cover 150 to better illustrate the internal configuration of components. FIG. 2A illustrates a perspective cross-sectional view of an example cover 150 for an omni-directional antenna 100, in accordance with one or more embodiments. FIG. 2B illustrates a cross-sectional view of an example omni-directional antenna 100, in accordance with one or more embodiments. In various embodiments, the components of cover 150 may be manufactured by various manufacturing processes, such as traditional machining, injection molding, 3D printing, or 20 various other manufacturing processes.

In example embodiments, cap 152 includes an outer cylinder portion 152-A and an upper cylinder portion 152-A. Base 154 includes an inner cylinder portion 154-A and a lower cylinder portion 154-B. Outer cylinder portion 152-A, upper cylinder portion 152-B, inner cylinder portion 154-A, and lower cylinder portion 154-B are depicted in FIG. 2B with variations in shading to better indicate the structure of 25 cap 152 and base 154 of cover 150. As illustrated, each of outer cylinder portion 152-A, upper cylinder portion 152-B, inner cylinder portion 154-A, and lower cylinder portion 154-B have an interior surface and an exterior surface. For example, outer cylinder portion 152-A includes exterior surface 152-A1 and interior surface 152-A2, while inner cylinder portion 154 includes exterior surface 154-A1 and interior surface 154-A2. The exterior surface 152-A1 and interior surface 152-A2 of outer cylinder portion 152-A may be continuous with the exterior surface and the interior surface, respectively, of the upper cylinder portion 152-B. additional support collar 107, which may be of various sizes (depicted in FIG. 2B). As depicted cable opening 214 and enlarged bore 216 are centered about the longitudinal center axis 11.

In various embodiments, an intercover space 210 may be formed between the interior surface 152-A2 of outer cylinder portion 152-A and the exterior surface 154-A1 of inner cylinder portion 154-A. In some embodiments, intercover space 210 may be an annular space which may be configured to house wire elements 250, as further depicted in FIGS. 3A and 3B. In some embodiments base 154 is configured to include wire notches 212 within the intercover space 210 for supporting and securing wire elements 250. In some embodiments wire notches 212 may be included on the cap 152, such as on the interior surface 152-A2 of the outer cylinder portion 152-A.

In some embodiments, the cover 150 may be configured such that the cap 152 is fit within base 154, such that the walls of the cap 152 may form the inner cylinder portion, while the walls of the base 154 may form the outer cylinder portion. In such embodiments, the intercover space 210 may be formed between an outer surface of cap 152 and an inner surface of base 154. In such embodiments, wire notches 212 may be located on the outer surface of cap 152 or the inner surface of base 154.

As shown in FIG. 2B, an inner support collar 107 may be positioned around cable 102. The support collar 107, along with cable 102, forms a center-fed sleeved dipole type central radiating element of antenna 100. In various embodiments, inner support collar 107 may be a metallic collar. For example, inner support collar 107 may be a $5/32$ " by 0.44" brass collar. Inner support collar 107 may be secured to the lower cylinder portion 154-B of base 154 with glue or other appropriate adhesive.

In some embodiments, inner support collar 107 may be soldered to cable 102 to secure support collar 107 in place relative to cable 102. In some embodiments one or more inner layers of cable 102 may be exposed from the outermost jacket layer. For example, the outer conductor layer of cable 102 may be exposed along the portion of cable 102 that is located within the inner support collar 107. Support collar 107 may be positioned to be level with an end of the exposed cable shield. In some embodiments, inner support collar 107 may be soldered to one or more portions of the outer conductor layer of cable 102. In some embodiments, upper portion 107-A of inner support collar 107 may include a smaller diameter in order to grip the corresponding portion of cable 102. For example, upper portion 107-A may be crimped with a crimping plier. This provides additional stability and forces cable 102 to remain centered with respect to support collar 107. In various embodiments, the crimping or other reduction in diameter of upper portion 107-A may affect the effective balancing of antenna 100 by changing the dielectric properties of the corresponding portion of cable 102 and causing support collar 107 to act as a balun, as well as a counter-element.

In some embodiments, a covering material 220 (shown in dashed lines) may cover a portion of the antenna 100 for insulation or protection from dust, dirt, wear, and/or damage. As shown in FIG. 2B, covering material 220 covers a bottom portion of lower cylinder portion 154-B to a top portion of coaxial RF connector 104. For example, covering material 220 may comprise heat shrink tubing or any other material with appropriate characteristics, such as non-conductivity, flexibility, or durability.

With reference to FIGS. 3A and 3B, shown are perspective views of a base 154 of an example cover 150 for an

omni-directional antenna 100, in accordance with one or more embodiments. As depicted in FIG. 3A, the location of cap 152 is shown as dotted lines to indicate where cap 152 may be situated relative to base 154.

In various embodiments, a plurality of conducting elements 250 is arranged equidistantly around center axis 11. As used herein, conducting elements may be referred to as wires, strips, or parasitic elements. In some embodiments, conducting elements 250 may be secured within intercover space 210. In some embodiments, conducting elements 250 may be positioned within cavity 202 or external to outer cavity portion 152-A. In example embodiments, conducting elements 250 are arranged equidistantly within the intercover space 210. In some embodiments, antenna 100 may include five (5) conductors 250. However any number of conductors may be included within intercover space 210. For example, there may be as few as three (3) wires or as many as eight (8) wires. In some embodiments, there may be fewer than three (3) wires or more than eight (8) wires. In various embodiments, conducting elements 250 may comprise any metal wire such as copper wires. For example, wire elements 250 may be 26 AWG wires. However, in various embodiments, conducting elements 250 may comprise any one of various metallic wires or strips with appropriate electromagnetic characteristics.

In some embodiments, the plurality of conducting elements 250 are configured to include an angle of tilt from horizontal. As shown in FIG. 3A, there is an angle θ between wire elements 250 and a horizontal axis 12. In various embodiments, the angle θ may be between 16 degrees and 68 degrees. For example wire elements 250 may be configured to include an angle of tilt of 42 degrees from horizontal. However, in other embodiments, the angle of tilt from horizontal of conducting elements 250 may be less than 16 degrees or more than 68 degrees. In example embodiments, the conducting elements 250 may be arranged to provide a right hand circular polarization (RHCP) or a left hand circular polarization (LHCP). As shown in FIG. 3A, the wire elements 250 are arranged to tilt diagonally upward to the right providing a left hand circular polarization. As shown in FIG. 3B, the wire elements 250 are arranged to tilt diagonally upward to the left providing a right hand circular polarization.

In some embodiments, conducting elements 250 may be secured to the outer cylinder portion 152-A and/or inner cylinder portion 154-A. For example, conducting elements 250 may be glued to a surface 154-A1 or 154-A2 of inner cylinder portion 154-A. In other examples, conducting elements 250 may be glued to a surface 152-A1 or 152-A2 of outer cylinder portion 152-A. In some embodiments, conducting elements 250 may be conductive materials embedded within a printed circuit board. The printed circuit board may be flexible enough to roll and/or bend about the circumference of inner cylinder portion 154-A. In some embodiments the length of the printed circuit board may cover the circumference of the exterior surface 154-A1 of inner cylinder portion 154-A. In some embodiments, the printed circuit board may be attached to a surface 154-A1 or 154-A2 of inner cylinder portion 154-A with glue or other appropriate adhesive. In some embodiments, printed circuit board may be attached to a surface 152-A1 or 152-A2 of outer cylinder portion 152-A with glue or other appropriate adhesive.

As illustrated, in some embodiments, the exterior surface 154-A1 of inner cylinder portion 154-A may include wire notches 212 configured to secure wire elements 250 with proper spacing and in appropriate orientations. In some

embodiments, a set of wire notches 212 comprise a lower notch 212-A and an upper notch 212-B which are aligned diagonally. Each set of wire notches 212 may form a channel in which a wire element may fit. In some embodiments, the channel formed by a set of wire notches 212 may be not be continuous. For example, as shown in FIGS. 3A and 3B, the lower notches 212-A are integrated within a lower rim 156-A of the inner cylinder portion 154-A, and the upper notches 212-B are integrated within an upper rim 156-B of the inner cylinder portion 154-A. However, in some embodiments, a track formed by notches 212 may be continuous along the height of inner cylinder portion 154.

In some embodiments, the inner cylinder portion 154 may include two series of notches 212. One series of notches may be used to arrange the wire elements for RHCP, while the other series of notches may be used to arrange the wire elements for LHCP. The wire elements may further be secured to inner cylinder portion 154-A with a glue or other appropriate adhesive. The wire elements 250 may be situated completely against the curved surface of the exterior surface 154-A1 of the inner cylinder portion 154, and thus the wire elements 250 may be curved along the exterior surface 154-A1 of the inner cylinder portion 154-A. In some embodiments, the wire elements 250 may be curved to the same degree as the exterior surface 154-A1 of the inner cylinder portion 154-A. In some embodiments the wire notches 212 may be attached to the interior surface 152-A2 of the outer cylinder portion 152, and the wire elements 250 may be secured to the outer cylinder portion 152. In various other embodiments, outer cylinder portion 152 or inner cylinder portion 154 may include other support structures to support or guide wire elements 250.

In various embodiments, cable 102 comprises a sleeved dipole that may be used as a feed and the active part of the antenna 100. In some embodiments, the wire elements 250 may function as parasitic radiating elements. In some embodiments, wire elements 250 may radiate out at 180 degrees from the center radiating element at a particular desired tuned frequency. For example, wire elements 250 form inductively resonant cage and the length, shape, and width of the wire elements and/or angle of tilt of the wire elements may change the harmonics of the radiation of the inductively resonant cage.

Because the conducting elements 250 are situated against the exterior surface 154-A1 of the inner cylinder portion 154-A, the conductors 250 may curve along with the exterior surface 154-A1 allowing the antenna size and gain to be adjusted. Because the conducting elements 250 are contained within intercover space 210 and fully covered by cap 152, the parasitic radiating elements of antenna are less subject to damage or wear as compared to other similar functioning antennas. For example, a Lindenblad antenna may use four, dipole, driven-elements to create a circularly polarized, omni-directional radiation pattern. As another example, a Yagi-Uda antenna may include several parasitic elements that serve as passive radiators to reradiate the radio waves to modify radiation patterns. However, such radiating elements are generally not covered and may be more subject to damage and wear.

In various embodiments, the length of cable 102 may vary. In some embodiments, the cable may be a 54 millimeter (2") 41 millimeter (1.65") RG405 coaxial cable. However, the length of cable 102 may be trimmed to achieve a desired standing wave ratio (SWR) at a given frequency, such as 5800 MHz.

In various embodiments, the frequency of operation (f) of antenna 100 may depend on a combination of the length and

size of cable 102, the length and placement of conducting elements 250, and the size of support collars 106 and 107. For example, for a given arrangement of components, the operation frequency (f) in gigahertz (GHz) may be approximated by the following equation:

$$f = \frac{5125}{H_c}$$

where H_c is the antenna head height of the cable 102 from first end 102-A in cavity 202 to the base of the support collar 107, as shown in FIG. 2B. The antenna head height H_c may also refer to the active section of the antenna 100. The radiation pattern may also depend on the distance of wire elements 250 from the center axis 11. The equations above may be approximations and may include a margins of error. For example, the frequency measurements based on the antenna head height may be about $\pm 20\%$.

With reference back to FIG. 2B, in some embodiments, cable 102 includes an total antenna length (L_a) from the first end 102-A of cable 102 to the base of coaxial RF connector 104. In some embodiments, the total antenna length (L_a) may correspond to the desired operation frequency of the antenna. For example, for a given arrangement of components, the total antenna length (L_a) of antenna 102, in inches, may be equal to approximately

$$\frac{f}{3625},$$

where f is the desired operation frequency in megahertz (MHz). The margin of error for the total antenna length (L_a) may be $\pm 25\%$.

The conducting elements 250 may be of various lengths in various embodiments. In some embodiments, the conducting elements 250 are of uniform length. In some embodiments, the conducting elements 250 may be positioned such that the centers of the conducting elements 250 are aligned at the same height position as the end of the top portion 107-A of inner support collar 107. The length (L_w) of the conducting elements may be approximated by the equation:

$$\frac{L_w}{f} = 3885$$

where L is the length of a wire element in inches, and f is the frequency in MHz. There is a margin of error of $\pm 20\%$ in this measurement depending on location and materials used.

As previously described, above conducting elements 250 are positioned within intercover space 210 along the external surface 154-A1 of the inner cylinder portion 154-A. In some embodiments, the radius, in inches, from the center axis 11 to the exterior surface 154-A1 of the inner cylinder portion 154-A (r_i) will typically range from

$$\frac{4350}{f} \text{ to } \frac{1160}{f};$$

11

where f is the desired operation frequency in MHz. In some embodiments, radius (r_i) may also correspond to the distance between the conducting elements 250 and the center axis 11.

FIG. 4 is an example radiation pattern graph 400 of an omni-directional antenna, in accordance with one or more embodiments. The graph shows radiation pattern of an example of a right hand circular polarization configuration of antenna 100. The graph shows the total gain 402 (outermost pattern), dominant rotation pattern 404 (middle pattern), and recessive pattern 406 (innermost pattern). The conducting elements may be reversed in direction to change the recessive and dominant antenna patterns from RHCP to LHCP and LHCP to RHCP. Additionally, the location of the conducting elements will change the pattern of the antenna.

FIG. 5 is an example method 500 of constructing an omni-directional antenna, in accordance with one or more embodiments. At step 501 a cable is inserted through a first support collar such that an annular cavity is formed within the first support collar around the cable. In some embodiments, the cable may be cable 102 and the first support collar may be support collar 106. At step 503, the first support collar is soldered to a first end of the cable. As previously described, cable 102 may include a coaxial RF connector 104 that is integral to cable 102 at a second end 102-B. Here, the first end of the cable may be the second end 102-B. As such, the support collar may be soldered to the coaxial RF connector portion of the cable. Step 503 may be performed by placing the cable in a solder rack with the support collar. Next, two half inch sections of 0.31" diameter solder material or one half inch section of about 0.62" diameter solder material may be placed into the annular cavity. The support collar may be inserted into an inductive heater for approximately 15 seconds until the solder is liquefied. Polyamide plastic may then be injected into any remaining space in the annular cavity until the annular cavity is completely filled and the polyamide plastic is level with the upper rim of the support collar.

At step 505, a second end of the cable is extended through an opening in a cover base, such as base 154 of cover 150. The cover base may include an inner cylinder portion, such as inner cylinder portion 154-A, having an interior surface 154-A2 and an exterior surface 154-A1. The second end of the cable, may be first end 102-A, is located within a cavity, such as cavity 202, defined by the interior surface 154-A2 of the inner cylinder portion 154-A, as depicted in previous FIG. 2B. The first end of the cable, such as second end 102-B, may be located external to the inner cylinder portion, as depicted in previous FIG. 2B. The cable is aligned with a center axis of the cover base, such as center axis 11.

At step 507, the cable may be inserted through a second support collar such that the second support collar surrounds a portion of the cable within the cavity. In some embodiments, the second support collar may be inner support collar 107 which surrounds a portion of cable 102 within cavity 202, as shown in FIG. 2B. In some embodiments, a top portion of the second support collar, such as top portion 107-A, may be crimped. For example, the first $1/16$ " to $1/8$ " of the top portion of the second support collar may be crimped with a 0.128" crimp tool. As previously described, the crimped portion of the second support collar may serve to grip against the cable and keep the cable centered relative to the second support collar. At step 509, the second support collar is soldered to the cable. In some embodiments, the second support collar may be soldered to an exposed cable shield of the cable, such as the outer conductor layer. In

12

some embodiments, the second support collar may also be attached to the cover base, such as within the enlarged bore 216.

At step 511, a plurality of conducting elements is positioned about the cylinder portion such that the wire elements are spaced equidistantly around cavity circumference around the center axis 11. The conducting elements may be attached via glue or other method. In some embodiments the conducting elements may be wire elements 250. As previously described, any number of conducting elements may be included. For example, antenna 100 may include five (5) wire elements spaced equidistantly around cavity 202.

At step 513, the cavity may be sealed by covering the cover base with a cover cap such that an outer cylinder portion of the cover cap surrounds the exterior surface of the inner cylinder portion. For example, the cover cap may be cap 152 of cover 150, and the outer cylinder portion may be outer cylinder portion 152-A. The cover cap may be secured to the cover base with a glue or other appropriate adhesive. Once secured in place, an intercover space, such as intercover space 210, may be formed between the outer cylinder portion of the cover cap and the inner cylinder portion of the cover base. The plurality of conducting elements may be located within such intercover space, as described with reference to FIGS. 2A, 2B, and 3A.

In some embodiments, each of the conducting elements may be configured to attach to the exterior surface of the inner cylinder at an angle with respect to horizontal. In some embodiments, the conducting elements may be configured to include an angle of tilt of about 42 degrees from horizontal. However, in some embodiments, the conducting elements may be configured to include an angle of tilt between 16 degrees and 68 degrees from horizontal. Each conducting element may include the same angle of tilt. In some embodiments, the conducting elements may be attached to other portions of the cover, such as cover 150. For example, conducting elements may be alternately attached to the interior surface of the outer cylinder portion of the cover cap.

As previously described, the conducting elements may be positioned such that the centers of the conducting elements are aligned at the same position as the end of the top portion of inner support collar of the second support collar, such as top portion 107-A of inner support collar 107. The conducting elements may also be placed at a certain distance from the cable or the center axis of the antenna, such as center axis 11.

With reference to FIG. 6, shown are examples of conductive elements within the plurality of conductive elements 250 embedded within a printed circuit board (PCB) 601. FIG. 6 illustrates an example of conductive elements within the plurality of conductive elements in which each element within the plurality of conductive elements 250 will incorporate a single curve around the central axis of the antenna. FIG. 6 illustrates an example of conductive elements within the plurality of conductive elements 250 embedded in a PCB 601 in which each element has multiple curve angles.

With reference to FIG. 6, each element within the plurality of conductive elements 250 is embedded within a printed circuit board (PCB) 601 is designed as a single curve conductor. The PCB 601 is made of a material which may be bent around or within a cylindrical structure. The PCB 601 may be made from a flexible PCB or made from thin fiberglass material such as FR4. The angle from horizontal

13

increases with the radius r_i of the antenna. The total length (L_w) of the conducting elements may be approximated by the equation:

$$\frac{L_w = 3885}{f}$$

where L_w is the length of a conductive element in inches, and f is the frequency in MHz. There is a margin of error of $\pm 20\%$ in this measurement depending on location and materials used.

With reference to FIG. 6 each element within the plurality of conductive elements 250 comprises multiple or compound curves. The bend in the conductive elements 250 may be an abrupt bend or be of a smoother curved type of bend. Each compound curve element within the plurality of conductive elements is embedded in a flexible printed circuit board (PCB) 601. The total length (L_w) of the conducting elements may be approximated by the equation:

$$\frac{L_w = 4930}{f}$$

where L_w is the length of a conductive element in inches, and f is the frequency in MHz. There is a margin of error of $\pm 25\%$ in this measurement depending on location and materials used.

In some embodiments each element in the plurality of conductive elements 250 comprises a horizontal portion 602 and an angled portion 603. An angle φ between the horizontal portion 602 and the angled portion 603 may range from 22 to 90 degrees. In specific embodiments the angle φ is 30 degrees.

With reference to FIG. 7A, shown is an example of the plurality of conductive elements 250 mounted within a printed circuit board 601 installed within a cylindrical non-conductive cover 152 to better illustrate the configuration of the antenna structure when the plurality of conductive elements is embedded within a printed circuit board (PCB) 601. The non-conductive cover 152 may be made from any non-conductive material such as polypropylene or polycarbonate plastic. The PCB 601 may be attached to the cylindrical cover by way of adhesive or friction and tension of the PCB 601.

With reference to FIG. 7B, shown is an example of the plurality of conductive elements 250 mounted on a cylindrical non-conductive cover 152. Each element within the plurality of conductive elements 250 may have one or more curves or angles.

With reference to FIGS. 8A, 8B, and 8C shown are assembly drawings of particular antennas with angular geometry in which the plurality of conductive elements 250 are embedded within a PCB 601. FIG. 8A illustrates an example embodiment in which the antenna comprises an angular geometry in which a non-conductive support structure 801 which is made with four (4) flat sides. Each element in the plurality of conductive elements 250 comprises multiple angles. Each element within the plurality of conductive elements is bent around the edge of each flat side of the non-conductive support structure 801 where the angle of the element changes. The plurality of conductive elements 250 is centered around the coaxial cable 102.

With reference to FIG. 8B, shown is an exploded view of an example embodiment with the non-conductive support

14

structure 801 opened apart to show the detail of the inside. A coaxial cable 102 extends through the center of the non-conductive support structure 801.

With reference to FIG. 8C, shown is an example plurality 5 of conductive elements 250 embedded within a PCB 802 which may be installed in an antenna 100 with angular geometry. The PCB 802 may be bent or curved around the non-conductive support structure 801 so that the PCB 802 is bent at the junction of the horizontal portion 602 and the angled portion 603 of the plurality of conductive elements 250.

FIGS. 9A and 9B are example models of various embodiments which show the detail of the conductive structures of the antenna without covers or caps for clarity. The central 15 portion of the model is a dipole comprised of the first end of the coaxial cable 102 and the inner collar 107. The plurality of conductive elements 250 are located equidistantly around the dipole formed by cable 102 and inner collar 107.

Although many of the components and processes are 20 described above in the singular for convenience, it will be appreciated by one of skill in the art that multiple components and repeated processes can also be used to practice the techniques of the present disclosure.

While the present disclosure has been particularly shown 25 and described with reference to specific embodiments thereof, it will be understood by those skilled in the art that changes in the form and details of the disclosed embodiments may be made without departing from the spirit or scope of the disclosure. It is therefore intended that the 30 disclosure be interpreted to include all variations and equivalents that fall within the true spirit and scope of the present disclosure. Although many of the components and processes are described above in the singular for convenience, it will be appreciated by one of skill in the art that 35 multiple components and repeated processes can also be used to practice the techniques of the present disclosure.

What is claimed is:

1. An antenna comprising:

a non-conductive cover comprising:

a base including an inner portion having an interior surface and an exterior surface; and
a cover including an outer portion;
wherein the base and the cover form a cavity interior to the inner portion;

a cable extending through an opening in the cavity such that a first end of the cable is located within the cavity and a second end of the cable is located external to the cover; and

an emitter central to the cover bonded to the coaxial cable; and

a plurality of conductive elements spaced equidistantly about a circumference around the center axis of the cover not electrically connected to the coaxial cable or the emitter.

2. The antenna of claim 1, wherein the plurality of conductive elements are curved about the circumference around the center axis of the cover.

3. The antenna of claim 1, wherein the plurality of conductive elements are located within an enclosure.

4. The antenna of claim 1, wherein each wire element of the plurality of conductive elements are configured to include an angle of tilt between 16 degrees and 68 degrees from horizontal.

5. The antenna of claim 1, wherein each wire element of the plurality of conductive elements are configured to include an angle of tilt of 42 degrees from horizontal.

15

6. The antenna of claim 1, wherein the plurality of conducting elements are included within a printed circuit board, the printed circuit board wrapped around the circumference around the center axis of the cover.

7. The antenna of claim 1, wherein the plurality of conducting elements includes five wire elements.

8. The antenna of claim 1, wherein each wire element of the plurality of conducting elements comprises a copper wire.

9. The antenna of claim 1, wherein the radius (re), in inches, from the center axis to the plurality of conducting elements is between

$$\frac{0.88}{f} \text{ and } \frac{4.24}{f};$$

wherein f is a desired operation frequency in gigahertz (GHz).

10. The antenna of claim 1, wherein the radius (ri), in inches, from the center axis to the plurality of conducting wire elements is equal to

$$\frac{2.6535}{f};$$

wherein f is a desired operation frequency in gigahertz (GHz).

11. The antenna of claim 1, wherein the cable is a coaxial cable.

12. The antenna of claim 1, wherein the second end of the cable includes a coaxial radio frequency (RF) connector.

13. A system comprising:

a receiver; and

an antenna, the antenna comprising:

an enclosure comprising:

a base having an interior surface and an exterior surface; and

a cap including an outer portion;

wherein the base and the cap form a cavity interior to a cylinder portion;

a cable extending through an opening in the enclosure such that a first end of the cable is located within the cavity and a second end of the cable is located external to the cover;

an emitter connected to the first end of the coaxial cable located within the cover;

a plurality of conducting elements not electrically bonded and spaced equidistantly about a circumference around the center axis of the cover operating in parasitic fashion.

14. The system of claim 13, wherein the antenna is coupled to the receiver via a coaxial radio frequency (RF) connector; wherein the coaxial RF connector is coupled to the second end of the cable.

15. The system of claim 13, wherein the cable is directly coupled to a circuit board of the receiver.

16. The system of claim 13, wherein the plurality of conducting elements are curved about the circumference around the center axis of the cover.

17. The system of claim 13, wherein each wire element of the plurality of conducting elements are configured to include an angle of tilt between 16 degrees and 68 degrees from horizontal.

16

18. The antenna of claim 12, wherein each wire element of the plurality of conducting elements are located within an enclosure.

19. A method for constructing an antenna, the method comprising

inserting a cable through a first support collar such that an annular cavity is formed within the first support collar around the cable;

soldering the first support collar to a first end of the cable; extending a second end of the cable through an opening in a cover base, the cover base including an inner cylinder portion having an interior surface and an exterior surface,

wherein the second end of the cable is located within a cavity defined by the interior surface of the inner cylinder portion and the first end of the cable is located external to the inner cylinder portion;

wherein the cable is aligned with a center axis of the cover base;

insert the second end of the cable through a second support collar such that the second support collar surrounds a portion of the cable within the cavity;

soldering the second support collar to the cable; positioning a plurality of conducting elements about the inner cylinder portion such that the conducting elements are spaced equidistantly around a circumference around the center axis, the plurality of conducting elements not electrically connected to the coaxial cable and operating in parasitic fashion; and

sealing the cavity by covering the cover base with a cover cap such that an outer cap surrounds the plurality of conducting elements.

20. The system of claim 19, wherein the plurality of conducting elements are curved about the circumference around the center axis of the cover.

21. The method of claim 19, wherein each wire element of the plurality of conducting elements are configured to include an angle of tilt between 16 degrees and 68 degrees from horizontal.

22. An antenna comprising:

a non-conductive cover forming an enclosure with an interior cavity;

a cable extending through an opening in the cavity such that a first end of the cable is located within the cavity and a second end of the cable is located external to the cover; and

a centrally located emitter electrically bonded to the first end of the coaxial cable; and

a plurality of conducting elements spaced equidistantly about a circumference around the interior cavity of a cylindrical cover wherein each element in the plurality of conducting elements includes a horizontal portion and an angled portion

wherein each element in the plurality of conducting elements includes a horizontal portion and an angled portion.

23. The antenna of claim 22, wherein the plurality of conducting elements is curved about the circumference around the center axis of the cover.

24. The antenna of claim 22, wherein the plurality of conducting elements is located within an enclosure.

25. The antenna of claim 22, wherein each wire element of the plurality of conducting elements incorporate a single curve around a central axis.

26. The antenna of claim 22, wherein each wire element of the plurality of conducting elements is configured to include an angle of tilt of 25 degrees from horizontal.

17

27. The antenna of claim 22, wherein the plurality of conductive elements is included within a printed circuit board, the printed circuit board located along the interior surface of a cylindrical cover.

28. The antenna of claim 22, wherein each wire element in the plurality of conducting elements incorporates multiple curves.

29. A plurality of conducting elements of claim 22, wherein each wire element is located within a printed circuit board.

30. A plurality of conducting elements of claim 22, wherein each element comprises a single curve.

31. A plurality of conducting elements of claim 22 in which the number of individual wire elements is between 2 and 16 individual elements.

32. A plurality of conducting elements of claim 22 in which the number of individual wire elements is four.

33. A plurality of conducting elements of claim 22, wherein each wire element comprises multiple curves including;

a horizontal portion; and

an angled portion.

34. A plurality of conducting elements of claim 33 in which an angle of between 22 and 90 degrees exists between the horizontal portion and the angled portion.

18

35. A plurality of conducting elements of claim 33 in which the angle between the horizontal portion and the angled portion is 30 degrees.

36. The antenna of claim 22, wherein the radius (r_i), in inches, from the center axis to a plurality of wire elements is between

$$\frac{0.88}{f} \text{ and } \frac{4.24}{f};$$

wherein f is a desired operation frequency in gigahertz (GHz).

37. The antenna of claim 22, wherein the radius (r_i), in inches, from the center axis to a plurality of wire elements is

$$\frac{1.14}{f};$$

wherein f is a desired operation frequency in gigahertz (GHz).
